FRONT SIGHT FOR FIREARMS

Benjamin A. Tetzlaff, Riverside, Ill.

Application January 29, 1937, Serial No. 123,030
Renewed December 17, 1938

1 Claim. (Cl. 33—47)

This invention relates to sights and has particular reference to front sights for firearms.

Among the objects of my invention is the provision of a novel shielded or hooded front sight embodying a tubular sighting member provided with a pair of interchangeable tubular hoods of different lengths, said hoods being screw-mounted on opposite ends of the sighting member and interchangeable one with the other for relative mounting on the ends of the sighting member to thereby adapt the use of such sight to varying light conditions.

Another object of the invention is found in the provision of a cylindrical sighting member having a cylindrical aperture support formed integrally with the sighting member by means of a pair of horizontal arms and a vertical arm.

A further object of my invention is to provide a tubular sighting member with a base, an aperture support, a pair of arms disposed parallelly to the base, and an arm disposed vertically to the base; all of the arms being formed integrally with the sighting member at their outer ends, and at their inner ends, integrally with the aperture support.

Another feature of my invention is found in the provision of a cylindrical hooded sight having an optically aligned cylindrical aperture member.

Still another feature of my invention resides in the novel design and arrangement of the parts and members whereby the hoods and the sighting member have aligned or flush outer surfaces so that there are no parts projecting outwardly of the sight which might become loosened, detached or damaged when the firearm on which such sight is mounted is inserted or withdrawn from a gun-case or the like.

With the above and other objects in view, my invention consists in the novel combination, construction and arrangement of the parts and members shown in preferred embodiment in the attached drawing, described in the following specification and particularly pointed out in the appended claim.

In the drawing:

Fig. 1 is a side elevation of an end of a firearm barrel showing my improved front sight;

Fig. 2 is a similar view showing the hoods in reverse position;

Fig. 3 is an end view of same;

Fig. 4 is an enlarged vertical section through the sight;

Fig. 5 is a section on line 5—5 of Fig. 4;

Fig. 6 is an enlarged view of the aperture adapter and its support; and

Figs. 7 and 8 show respectively, side and top views of the adapters and their mounting plate.

In the drawing, which illustrates a preferred embodiment of my invention, the numeral 10 indicates the front or discharge end of a rifle provided with a transversely disposed dove-tailed groove 11 adapted to receive the dove-tailed base 12 of a tubular, and preferably cylindrical, 10 sighting member 13.

The opposite ends of the cylindrical sighting member 13 extend preferably substantially equal distances beyond the sides of the base 12 and are exteriorly threaded, as at 14, to receive the cylindrical hoods 15 and 16. These hoods are of like diameters and their outside diameters are preferably equal to the outside diameter of the sighting member 13, as clearly shown in Fig. 4. The outer ends of the cylindrical hoods 15 and 16 are preferably provided with peripheral flanges, respectively 15^A and 16^A, disposed inwardly of the aligned sighting bores 15^B and 16^B, and the diameter of the openings at such flanged ends being preferably equal to the inside diameter of the cylindrical wall of the sighting member 13.

It will be noted that the sighting member 13 is provided with a support adapted to receive any one of a plurality of aperture adapters 17, which adapters are provided with transverse walls 17^A having sighting apertures 18 of different diameters. The adapters may for convenience be furnished screw-mounted on a plate 19 as shown in Figs. 7 and 8.

The adapters 17 are preferably machined on 35 the inside from the opposite ends to form the apertured wall 17^A as an integral part of the tubular wall of the adapter.

The support for the sighting aperture adapter 17 consists of a comparatively short cylindrical 40 portion 20, disposed centrally of the cylindrical member 13, and having comparatively thin narrow arms 21 and 22 formed integrally therewith and integrally with the wall of the cylindrical member 13.

The arms 21 are disposed on a horizontal line passing through the center of the optical axis of the sight and are parallel to the bottom face of the base 12, whereas the arm 22 is disposed vertically to the bottom face of the base 12 on 50 a vertical line passing through the center of the optical axis of the sight. Since the sighting bores of the hoods 15 and 16 and that of member 13 is substantially preferably three times the diameter of the adapter 17 it is readily seen that 55

this sight provides a large field of vision outside of the wall of the adapter 17 for observation of the target or object aimed at, and furthermore, the horizontal and vertical positioning of the arms 21 and 22 affords a detection of 5 cant in the position of the firearm barrel.

The cylindrical adapter support 20 is threaded interiorly from the outer end thereof to receive the exteriorly threaded end 17^B of the adapter 17.

10 The arrows in Figs. 1 and 2 indicate the direction of sighting through the sight. When the light is directed toward the object or forwardly of the firearm barrel, the longer of the hoods 16 is mounted on the rear end of the member 13 as shown in Fig. 1, but if the light is directed 15 toward the end of the firearm barrel, the shielding of the sighting aperture in such front sight is more effected by a reverse mounting of such hoods on the member 13 as clearly shown in 20 Fig. 2.

It will be readily understood that the diameter and length of the cylindrical support 20 may be varied, that is, its thickness could be 25 equal to the thickness of the arms 21 and 22; and if desired, the inner and outer diameters of the portion 20 could be such that the same would constitute a fixed sighting aperture.

I claim:

30

A front sight comprising a cylindrical sighting member having threaded ends and a dovetailed supporting base member disposed between the threaded ends; an interiorly threaded cylindrical support disposed concentrically with said cylindrical sighting member, said cylindrical support being substantially shorter than said cylindrical sighting member; a pair of laterally aligned narrow arms disposed parallel to the bottom face of said supporting base member on a horizontal line passing through the optical axis of the sight; a narrow arm disposed perpendicularly to the bottom face of said supporting base member on a vertical line passing through the optical axis of the sight; said arms being integral 15 with said cylindrical support and with the wall of said cylindrical sighting member and extending in a plane common to adjacent ends of said cylindrical sighting member and said cylindrical support; an adapter having an apertured 20 sighting diaphragm therein, said adapter having a threaded end adapted to be screw-mounted within said cylindrical support; and a pair of elongated open end hoods screw-mounted on the threaded ends of said cylindrical sighting member, said hoods being of relatively different 25 lengths and being interchangeable for relative mounting on the ends of said cylindrical sighting member.

BENJAMIN A. TETZLAFF. 30
